(57) **CLAIM**

The ornamental design for a single serve funnel packet, as shown and described.

DESCRIPTION

FIG. 1 is a front view of a single serve funnel packet showing my new design;

FIG. 2 is a top view thereof;

FIG. 3 is a bottom view thereof; and,

FIG. 4 is a left side view thereof; the right side view being a mirror image thereof.

The broken lines at the top edge and bottom edge of the single serve funnel packet form no part of the claimed design.

The bolded or heavy line weight dashed lines within the claimed design illustrate the tear strips of the single serve funnel packet.

In the drawings, the bolded or heavy weight dashed lines depict claimed tear strips of the single serve funnel packet.
